(57) **CLAIM**

The ornamental design for a data storage device, substantially as shown and described.

DESCRIPTION

FIG. 1 is a rear view of the data storage device.

FIG. 2 is a front view of a data storage device.

FIG. 3 is a left side view of the data storage device.

FIG. 4 is a right side view of the data storage device.

FIG. 5 is a top view of the data storage device.

FIG. 6 is a bottom view of the data storage device.

FIG. 7 is a rear view of the data storage device with a portion thereof extended.

FIG. 8 is a front view of the data storage device with a portion thereof extended.

FIG. 9 is a left side view of the data storage device with a portion thereof extended.

FIG. 10 is a right side view of the data storage device with a portion thereof extended.

FIG. 11 is a top view of the data storage device with a portion thereof extended; and,

FIG. 12 is a bottom view of the data storage device with a portion thereof extended.

The broken lines immediately adjacent the claimed structure in FIG. 5 represent the bounds of the data storage device and form no part of the claimed design.
